UNITED STATES PATENT OFFICE.

ANDREW P. OLSON, OF CHICAGO, ILLINOIS.

RADIATOR.

1,120,404.

Specification of Letters Patent. Patented Dec. 8, 1914.

Application filed May 20, 1913. Serial No. 768,745.

To all whom it may concern:

Be it known that I, ANDREW P. OLSON, a citizen of the United States, residing at Chicago, in the county of Cook and State 5 of Illinois, have invented certain new and useful Improvements in Radiators, of which the following is a specification, reference being had therein to the accompanying drawing.

10 My invention relates to radiators for explosive or gas engines and consists in the matters hereinafter described and then pointed out in the appended claims.

15 In the accompanying drawings illustrating a practical embodiment of my invention—Figure 1 is a side view of an explosive engine equipped with my invention; Fig. 2 is a front view in elevation of the parts of Fig. 1; Fig. 3 is a rear view in elevation of the radiator casing with the fan and water distributer omitted; Fig. 4 is a vertical sectional view on the line 4—4 of Fig. 3; Fig. 5 is a side view in elevation of the fan and water distributer; Fig. 6 is a 20 front view of the same, and Fig. 7 is a detail view.

25 In the drawings the reference numeral 10 indicates the cylinder of a gas or explosive engine of any type in which water-cooling is employed, it being understood that as many cylinders may be used as may be required, provided with water circulating outlet pipe 11 and inlet pipe 12 by which water is usually supplied to the water-jacket 30 by a pump 13 in the supply pipe 14, the pipes 11 and 14 communicating respectively with the top and bottom of the radiator. The casing of the radiator is of sheet metal of any suitable size and shape having front, 35 rear, 15^a, sides, 15^b, top, 15^c, and bottom, 15^a, walls. The casing forms a water-collecting chamber and its lower portion provides a water reservoir or tank. The pipe 11 leads through the upper portion of the 40 rear wall to an upper header 16 located in a recess 17 formed by an inset 18 in the upper portion of the front wall of the radiator as shown in Figs. 2 and 4 and provided with a plurality of depending water-cooling 45 or radiating tubes or pipes 19 uniting in a lower header 20 at their lower ends, the lower header being located at about the center of a circular passage 21 formed in the front wall of the radiator. At the opening

21 and co-incident with its periphery a rear- 55 wardly extending cylindrical wall or parti- 50 tion 22 is secured which is slightly flared or enlarged toward its rear edge which ex- 55 tends within but circumferentially clears a corresponding circular passage 23 in the rear wall of the radiator as shown in Figs. 3 and 4 to leave an annular opening 24 be- 60 tween the periphery of the passage and the partition. The cylindrical partition forms an intermediate drum which is of less diam- 65 eter than the height and width of the body of the radiator so that passage is afforded between the two, and the lower portion of the drum is provided with a door 25 hinged at 26 and having a suitable latch 27 to allow 70 water to be poured into the lower interior portion of the radiator casing which forms the tank or reservoir with which the water- 75 supply pipe 14 communicates. The space between the inner sides of the radiator cas- 80 ing and the drum 22 is provided with retard- 85 ing or baffle plates which may be arranged in any suitable manner, and in the practical form shown I provide upper and lower im- 85 perforate plates 28 and 29 respectively ex- 90 tending outwardly from the drum toward the sides of the radiator body where they afford lateral passages 30 and 31 respec- 95 tively, and also with upper and lower per- 100 forated plates 32 and 33 respectively which preferably are slightly dished at their centers, the plates 32 being intermediate the plates 28 and 29. Below the drum and extending across the depth of the radiator casing I place a pair of oppositely inclined 105 baffle plates 34 and 35 which extend from opposite sides of the radiator body and afford opposite lateral passages 36 and 37 respectively, the latter leading into the water tank or reservoir formed by the lower por- 110 tion of the casing. Where the radiator is asso- 115 ciated with external engine cranking devices, such for example as the handle shown at 38, the lower portion of the tank or reservoir is provided with a passage for the extended 120 portion of the engine crank-shaft 39 formed by an arched partition or wall 40 which then divides the tank into opposite chambers 125 which are connected by a pipe 41 so that the water supply pipe 14 may draw from both. The pipe 41 is detachable so that 130 the radiator can be assembled on the ma- 135 chine.

The fan 42 is provided with a shaft 43 supported in a suitable bearing 44 and driven in any suitable manner as for example by a drive pulley 45 which is driven 5 by a belt 46 from a pulley 47 on the engine shaft 39, the shaft being located co-axially with the drum. The fan is provided with a hollow hub 48 closed at the rear and having an axial circular opening 49 at its front 10 to receive the free end of a pipe 50 secured to the lower header 20, the arrangement being such that the pipe and hub make a suitable joint to allow the latter to freely revolve about the former. The hub is provided 15 with a plurality of radial discharge pipes 51 preferably arranged tangentially on the hub and at a short distance from the fan blades so that air circulates between them, and each having a water-deflector plate 52 located in the hub at the opening to the 20 pipe; as shown in Fig. 6 when the hub revolves in the direction of the feathered arrow the centrifugal action will cause the water to enter the pipes as shown by the 25 featherless arrows. The pipes 51 extend radially to substantially the outer line of the fan blades where they connect with the interior of a peripheral annulus or circular rim formed by the pipe 53 which is divided 30 into chambers, preferably one for each radial pipe, by partitions 54 preferably placed intermediate the openings of adjacent pipes. Each chamber of the annular pipe 53 is provided slightly in the rear of its partition 35 considered with reference to the direction of movement of the pipe with an air vent or supply opening 55, and adjacent its partition or closure 54 with a discharge or exhaust opening 56 having a discharge pipe 40 57 which is curved and extends through the annular passage 24 into the interior of the radiator body and outside the drum. Each air vent 55 is provided with an air-intake or deflector plate preferably in the form of a 45 forwardly directed outwardly flared funnel 58 by which the air is directed under pressure into the corresponding chamber of the annular pipe 53 when the fan revolves.

When the fan and water-circulating pump 50 are operated water is drawn by the latter from the supply in the tank or reservoir in the lower portion of the body of the radiator and is circulated through the water-jackets of the engine cylinders to the return pipe 55 11, header 16, cooling or radiating pipes 19, and lower header 20 from whence it passes to the hub 48 of the fan and by centrifugal action through the pipes 51 to the chambers in the annular pipe 53 and out through 60 the exhaust pipes 57 by which it is discharged into the interior of the body of the radiator beyond or outside the drum. As the pipe 53 revolves with the fan in the direction of the feathered arrow in Fig. 6, atmospheric air is forced by the funnels 58

into the chambers of the pipe in advance of the water content of each chamber and is mixed with the water therein and discharged with the water through the exhaust pipes 57 in a finely divided aerated spray 70 around the drum 22, the air serving to cool the water. The particles of water pass over one or more of the baffle plates according to their respective points of exit from the pipes 57 and are further cooled in the 75 passage back to the tank, the surplus air passing out of the interior of the body of the radiator through the annular opening 24. By the time the water reaches the tank its 80 temperature is reduced to a point sufficient to enable it to again act as a cooling medium for the engine cylinders.

While I prefer to employ radiating pipes, such for example as shown at 19, in front of the fan to initially reduce the temperature of the water coming from the water-jackets of the cylinders, I may dispense with them and lead the water directly into the hub.

It frequently occurs in cold weather that 90 the circulation of the water by the construction described cools it below a desirable temperature, and I may therefore arrange a cut-off whereby some or all of the water coming from the pipe 11 may be cut off from 95 the revolving distributor and returned directly to the tank. For this purpose I may provide a by-pass controlled by a suitable valve; this may be suitably accomplished by providing the lower header with an outlet pipe 59 leading to the tank or reservoir and a valve 60 which may be turned by its handle 61 to position to alternately open and close the pipes 50 and 59, either wholly or partially according to the requirements of 100 any conditions of use. Where such by-pass is employed I preferably employ a pair of pipes 59 whose communication with the header is controlled by the valve and whose lower ends are spread apart so as to brace 110 and steady the header.

Various changes may be made without departing from the scope of my invention; for example, the revolving distributor may be used with or without a circulating pump 115 as the centrifugal action of the distributor may be sufficient to draw the water from the tank, and with or without the radiating pipes 19.

I claim:—

1. In a device of the class described, a radiator casing providing an interior water collecting chamber and a water reservoir, a revolving water distributor communicating with said reservoir and having air supply inlets whereby air and water are mixed in the distributor and also outlets to discharge the mixed air and water therefrom into the collecting chamber of the casing.

2. In a device of the class described, a

- radiator casing providing an interior water collecting chamber and a water reservoir, a revolving water distributer communicating with said reservoir and having a plurality of chambers each provided with an air inlet whereby air and water are mixed in the chamber and with an outlet to discharge the mixed air and water therefrom into the collecting chamber of the casing.
5. In a device of the class described, a radiator casing providing an interior water collecting chamber and a water reservoir, a revolving water wheel having a hollow hub communicating with said reservoir, pipes radiating from the hub, a hollow rim divided into chambers each having an air inlet and communicating with a radial pipe in the rear of its air inlet and discharge outlets from the rim into the collecting chamber of the casing.
10. 3. In a device of the class described, a radiator casing providing an interior water collecting chamber and a water reservoir, a revolving water wheel having a hollow hub communicating with said reservoir, pipes radiating from the hub, a hollow rim formed with chambers with which the radial pipes respectively communicate, a discharge outlet from each chamber into the collecting chamber of the casing, and an air vent in each rim-chamber in advance of its discharge outlet.
15. 4. In a device of the class described, a radiator casing providing an interior water collecting chamber and a water reservoir, a revolving water wheel having a hollow hub communicating with said reservoir, pipes radiating from the hub, a hollow rim formed with chambers with which the radial pipes respectively communicate, a discharge outlet from each chamber into the collecting chamber of the casing, and an air vent in each rim-chamber in advance of its discharge outlet.
20. 5. In a device of the class described, a radiator casing providing an interior water collecting chamber and a water reservoir, a revolving water wheel having a hollow hub communicating with said reservoir, pipes radiating from the hub, a hollow rim formed with chambers with which the radial pipes respectively communicate, a discharge outlet from each chamber into the collecting chamber of the casing, and an air vent in each rim-chamber in advance of its discharge outlet.
25. 6. In a device of the class described, a radiator casing providing an interior water collecting chamber and a water reservoir, a revolving water wheel having a hollow hub communicating with said reservoir, pipes radiating from the hub, a hollow rim formed with chambers with which the radial pipes respectively communicate, a discharge outlet from each chamber into the collecting chamber of the casing, and an air vent in each rim-chamber in advance of its discharge outlet, and a forwardly facing air-collector for each air vent.
30. 7. In a device of the class described, a radiator casing providing an interior water collecting chamber and a water reservoir, radiating pipes connected with the reservoir, a revolving fan in rear of the radiating
35. pipes having a hollow hub opening toward said pipes and revolvably communicating therewith, and a water distributer mounted on and leading from the hub and having means to mix air and water therein and to discharge the mixed air and water therefrom into the collecting chamber of the casing.
40. 8. In a device of the class described, a radiator casing providing an interior water collecting chamber and a water reservoir, radiating pipes connected with the reservoir, a revolving fan in rear of the pipes and having a hollow hub communicating therewith, pipes radiating from the hub, a hollow rim communicating with the radial pipes, and discharge outlets from the rim into the collecting chamber of the casing.
45. 9. In a device of the class described, a radiator casing providing an interior water collecting chamber and a water reservoir, radiating pipes connected with the reservoir, a revolving fan in rear of the pipes and having a hollow hub communicating therewith, pipes radiating from the hub, a hollow rim having chambers communicating respectively with the radial pipes, discharge outlets from the rim-chambers into the collecting chamber of the casing, and means to pass air into the rim-chambers in advance of their discharge outlets.
50. 10. In a device of the class described, a radiator casing providing an interior water collecting chamber and a tank or reservoir, a drum forming a central passage through the chamber, retarding plates in the chamber, a water-return pipe in the drum, water-supply connections leading from the reservoir to the return pipe in the drum, a water distributer in communication with said return pipe, and exhaust pipes leading from the water distributer to the water collecting chamber of the casing.
55. 11. In a device of the class described, a radiator casing providing an interior water collecting chamber and a tank or reservoir, a drum forming a central passage through the chamber, retarding plates between the drum and casing, a revolving water distributer in communication with said reservoir, exhaust pipes discharging from the water distributer to the water collecting chamber of the casing, and retarding plates in the casing above the water reservoir.
60. 12. In a device of the class described, a radiator casing providing an interior water collecting chamber and a tank or reservoir, a drum forming a central passage through the chamber, a water-return pipe in the passage, retarding plates on the drum extending toward the casing, water-conducting means from the reservoir to the return pipe in the drum, a revolving water distributer in communication with said return pipe, exhaust pipes leading from the water-distrib-

uter to the water collecting chamber of the casing, and retarding plates in the casing above the water reservoir.

13. In a device of the class described, a radiator casing providing an interior water collecting chamber and a tank or reservoir, a drum forming a central passage through the chamber, a water-return pipe in the passage, retarding plates on the drum extending toward the casing, perforated retarding plates between the drum and casing, water-conducting means from the reservoir to the return pipe in the drum, a revolving water distributer in communication with said return pipe, exhaust pipes leading from the water-distributer to the water collecting chamber of the casing, and retarding plates in the casing above the water reservoir.

14. In a device of the class described, a radiator casing providing an interior water collecting chamber and a tank or reservoir, a drum forming a central passage through the chamber, a water-return pipe in the passage, a water radiator connected with the reservoir and the return pipe in the drum, a revolving water wheel having a hollow hub in communication with said return pipe, exhaust pipes leading from the wheel to the water collecting chamber of the casing, a by-pass to the tank communicating

with the water radiator, and a valve to control the passage of the water to the by-pass and hub.

15. In a device of the class described, a radiator casing providing an interior water collecting chamber and a tank or reservoir, a water radiator connected with the reservoir, a revolving water-wheel in rear of the water radiator discharging into the casing, a pipe leading to the wheel from the water radiator, a by-pass to the tank around the pipe, and a valve to control the passage of the water to the by-pass and water-wheel.

16. In a device of the class described, a radiator casing providing an interior water collecting chamber and a tank or reservoir, a water radiator connected to the reservoir, a revolving water-wheel in rear of the water radiator discharging into the casing, a pipe leading to the wheel from the water radiator, a by-pass to the tank communicating with the water radiator, and a valve to control the passage of the water to the by-pass and water-wheel.

In testimony whereof I affix my signature in presence of two witnesses.

ANDREW P. OLSON.
